UNITED STATES PATENT OFFICE.

ALBERT F. FREELAND, OF MALDEN, AND CHARLES H. WHITTEN, OF WALTHAM, MASSACHUSETTS.

WATCH-MOVEMENT BOX.

SPECIFICATION forming part of Letters Patent No. 325,204, dated August 25, 1885.

Application filed November 28, 1884. (No model.)

To all whom it may concern:

Be it known that we, ALBERT F. FREELAND, of Malden, in the county of Middlesex and State of Massachusetts, and CHARLES H. WHITTEN, of Waltham, in the county and State aforesaid, citizens of the United States, have invented certain Improvements in Watch-Movement Boxes, of which the following is a full, clear, and exact description, reference being had to the accompanying drawings, making part of this specification, in which—

Figure 1 is a perspective view of our improved watch-movement box, with the movement-holder in place therein and the cover removed. Fig. 2 is a central vertical section of the same with the watch-movement therein and the cover in place. Fig. 3 is a view of the movement-holder removed from the box. Fig. 4 is a plan of the under side of the holder with a watch-movement therein. Fig. 5 is a modification to be referred to.

Our invention consists in a watch-movement packing-box having a removable holder of peculiar construction, which contains the watch-movement and confines it securely within the box, and when removed from the latter forms a convenient stand or device provided with legs or feet for supporting the movement above the level of the sales counter, or other surface upon which it may be placed, thus avoiding the liability of the movement becoming injured by laying it down when out of the box.

In the said drawings, A represents a watch-movement box, preferably composed of tin and provided, as usual, with a cover, b. Around the periphery of this box A, at the junction of the side portion, c, with the bottom a, is an outwardly-projecting bead, forming on the inside of the box an annular groove, d, as seen in Fig. 2.

B is the watch-movement holder, which consists of a flat circular band or ring of brass, or other suitable material, of the proper diameter, to contain the watch-movement C, and of such width as to extend from the top plate to the case-shoulder. The lower edge of the holder B is turned slightly inward, forming a flange, f, which fits close up to the top plate of the movement, and over this flange are turned

the heads of the case-screws g, as seen in Fig. 4, for the purpose of confining the movement securely in place within the holder, a case-pin fitting into an aperture in a lug, i, at the upper edge of the band B serving as an additional means of holding the movement in place; but this lug i may be dispensed with, if desired, where there are two or more case-screws g. The holder B is provided at its lower edge with spring feet or legs k, preferably made integral therewith and extending outward therefrom, as seen in Fig. 3; and when the holder B is placed within the box A and pressed down therein these feet yield slightly and spring or snap into the groove d, when the holder, with the movement therein, will be confined securely in place within the box A entirely out of contact with the side portion, c, or bottom a, and with its dial in such position as to prevent the hands from coming into contact with the cover b, all rattling or looseness of the movement within the box A being thus prevented.

If preferred, the box A may be provided with an inwardly-projecting bead instead of the groove d, in which case the feet k will spring or snap under the bead, as seen in Fig. 5; but this device we regard as the full equivalent of the groove. At the upper edge of the box A, at points diametrically opposite each other, are two open slots, m, to enable the holder B to be conveniently grasped by the thumb and finger in the operation of placing it and the movement within the box or removing them therefrom, to facilitate which the sides of the box A may be slightly compressed by the hand, to admit one of the feet k to the groove d or release it therefrom at the point where the diameter of the box is elongated by the compression.

When the box is intended to contain a stem-winder movement, a suitable slot or notch is formed at the upper edge of the holder B to admit the winding-stem, which will extend nearly out to the side c of the box A.

The band B, when removed from the box A, can be set down on the feet k, and thus forms a very convenient stand or holder for the movement contained therein when taken out of the box, as the feet k serve to support the

movement in a horizontal position above the level of the sales counter or other surface on which it may be placed, and thus protect it from injury by contact therewith, as is liable to occur when a movement is taken out of an ordinary box and laid down in direct contact with a counter or other surface, a great advantage being thus gained. Furthermore, our improved box is of exceedingly simple construction, possesses few parts, and is not liable to get out of order.

What we claim as our invention, and desire to secure by Letters Patent, is—

1. The combination, with a watch-movement box or casing, A, having an interior peripheral groove or bead at or near its bottom, of the removable movement-holder B, provided with spring feet or legs k, adapted to support the same in a horizontal position when out of the box and spring into or engage with said groove or bead when the holder is placed within the

box, substantially as and for the purpose set forth.

2. The removable holder B, adapted to contain the watch-movement and provided with a flange, f, around its lower edge, over which are turned the case-screws g of the movement, to confine the latter within the holder, and having outwardly and downwardly projecting spring feet or legs k, in combination with the box A, provided with a peripheral groove, d, at or near its bottom, for the reception of the lower ends of the feet k, all constructed to operate substantially in the manner and for the purpose described.

Witness our hands this 24th day of November, A. D. 1884.

ALBERT F. FREELAND.
CHARLES H. WHITTEN.
